(57) **CLAIM**

The ornamental design for an illuminated control device, as
shown and described.

DESCRIPTION

FIG. 1 is a front perspective view showing a first state in a
sequence of an illuminated control device showing our new
design;

FIG. 2 is a front view thereof;

FIG. 3 is a left side view thereof;

FIG. 4 is a right side view thereof;

FIG. 5 is a top view thereof;

FIG. 6 is a bottom view thereof;

FIG. 7 is a front perspective view showing a second state in
a sequence thereof;

FIG. 8 is a front view thereof;

FIG. 9 is a left side view thereof;

FIG. 10 is a right side view thereof;

FIG. 11 is a top view thereof;

FIG. 12 is a bottom view thereof;

FIG. 13 is a front perspective view showing a third state in
a sequence thereof;

FIG. 14 is a front view thereof;

FIG. 15 is a left side view thereof;

FIG. 16 is a right side view thereof;

FIG. 17 is a top view thereof;

FIG. 18 is a bottom view thereof;

FIG. 19 is a front perspective view showing a fourth state in
a sequence thereof;

FIG. 20 is a front view thereof;

FIG. 21 is a left side view thereof;

FIG. 22 is a right side view thereof;

FIG. 23 is a top view thereof;

FIG. 24 is a bottom view thereof;

FIG. 25 is a front perspective view showing a fifth state in
a sequence thereof;

FIG. 26 is a front view thereof;

FIG. 27 is a left side view thereof;

(Continued)

FIG. 28 is a right side view thereof;
 FIG. 29 is a top view thereof;
 FIG. 30 is a bottom view thereof;
 FIG. 31 is a front perspective view showing a sixth state in a sequence thereof;
 FIG. 32 is a front view thereof;
 FIG. 33 is a left side view thereof;
 FIG. 34 is a right side view thereof;
 FIG. 35 is a top view thereof;
 FIG. 36 is a bottom view thereof;
 FIG. 37 is a front perspective view showing a seventh state in a sequence thereof;
 FIG. 38 is a front view thereof;
 FIG. 39 is a left side view thereof;
 FIG. 40 is a right side view thereof;
 FIG. 41 is a top view thereof;
 FIG. 42 is a bottom view thereof;
 FIG. 43 is a front perspective view showing an eighth state in a sequence thereof;
 FIG. 44 is a front view thereof;
 FIG. 45 is a left side view thereof;
 FIG. 46 is a right side view thereof;
 FIG. 47 is a top view thereof; and,
 FIG. 48 is a bottom view thereof.

The gray shaded elements depict illumination.
 The broken lines illustrate portions of the control device which form no part of the claimed design.
 The appearance of the claimed design sequentially transitions between the eight states shown in FIGS. 1-6, FIGS. 7-12, FIGS. 13-18, FIGS. 19-24, FIGS. 25-30, FIGS. 31-36, FIGS. 37-42, and FIGS. 43-48. The process or period in which one state transitions to another state forms no part of the claimed design.
